UNITED STATES PATENT OFFICE.

GEORGE WILLIAM BAYLEY, OF NEW YORK, N. Y.

ACETYLENE-GAS LAMP.

SPECIFICATION forming part of Letters Patent No. 628,912, dated July 18, 1899.

Application filed July 29, 1898. Serial No. 687,161. (No model.)

To all whom it may concern:

Be it known that I, GEORGE WILLIAM BAYLEY, of New York city, borough of Brooklyn, in the county of Kings and State of New York, 5 have invented a new and Improved Acetylene-Lamp, of which the following is a full, clear, and exact description.

My invention relates to an improvement in acetylene-lamps of that class in which an excess of carbid is used and the generation of the gas is regulated by controlling the supply of water.

My invention comprises the novel features hereinafter described and claimed.

Reference is to be had to the accompanying drawings, forming a part of this specification, in which similar characters of reference indicate corresponding parts in all the figures.

Figure 1 is a central sectional elevation of 20 my lamp. Fig. 2 is a sectional plan taken upon the line 2 2 of Fig. 1, and Fig. 3 is a vertical section of a removable cartridge to be used with my lamp when desired.

My device comprises an inner and an outer 25 case, the inner of which contains the carbid and the outer the water. Between the two is placed a valve which is controlled by the pressure of the gas, so as to admit water to the carbid when the pressure falls below a 30 fixed point and to close the valve as soon as the pressure rises above the fixed point.

The outer case A is made of any convenient or desired shape, but preferably circular. This case is made with a removable cap or 35 covering, by which the inner case, containing the carbid, may be removed or inserted, as desired. The cap A' is secured at its lower edge to a ring B', which is exteriorly threaded and screws within an interiorly-threaded ring B, 40 which is secured to the upper edge of the body A of the outer case. Between the two rings B' and B is inserted a packing-ring B², of rubber, leather, or similar material. The lower ring B, which is secured to the upper part of 45 the base or body of the outer case A, is provided with a recess adapted to receive a flange C' upon the inner case C. The inner case C is made as a cup, having an open top which is covered by a cap C², said top having perforations C³ therein, permitting the escape of 50 the gas. The flange C' fills the recess in the ring B and supports the inner case C at a

proper elevation. The inner case C is the carbid holder or generator, and projecting upward centrally from its bottom is a cylinder 55 E, which contains the valve mechanism by which the water is admitted to the carbid-holder or cut off, as desired. The cylinder E has a cap E' screwed or otherwise secured to the upper end thereof. It is also provided 60 with a number of holes e in its side, adapted to admit water to the carbid-holder. Within this cylinder is placed a valve F, which valve, as herein shown, consists of two pistons spaced a short distance apart and provided 65 with packing-rings F³ in their periphery. These packing-rings may be omitted if the fit of the piston within the cylinder is carefully regulated.

The stem F' of the valve is hollow and at 70 its lower end passes through an opening in the bottom of the cylinder E. The valve is normally held down, so as to close the openings e in the cylinder by a spring F², which is placed between the upper end of the valve 75 and the cap E'. The lower end of the stem F' engages a flexible diaphragm D, which closes an opening in the bottom of the outer case A. This diaphragm is held by its edges between the bottom of the outer case and a 80 ring D', which is secured thereto. This ring is threaded, as is also a cap D², which is screwed thereon and forms a support for a spring D³, which bears against the under side of the diaphragm D. The spring D³ is stronger 85 than the spring F² and will, if permitted, hold the valve elevated, so that the water is freely admitted from the outer case into the carbid-holder.

The water for generation of gas is placed 90 within an annular water-reservoir G, which is placed in the upper portion of the outer case and surrounds the inner case or carbid-holder. This water-reservoir is formed by an inner wall G³ and a bottom G⁴, which are 95 secured to the outer wall of the casing so as to make a water-tight chamber. This chamber is filled through a cup G', which may be unscrewed from the outside. In the reservoir is placed a valve by which the water may 100 be permitted to flow into the lower portion of the outer case and then be admitted to the valve F.

Until it is desired to use the lamp the wa-

ter is retained in the reservoir G, where it cannot by any possibility come in contact with the carbid. When it is desired to light the lamp, the valve in the bottom of the water-reservoir is opened, thus permitting the water to run into the space between the inner and outer cases.

The valve, as herein shown, consists of a cylinder g, perforated longitudinally to form a tube and inserted through the water-reservoir. The lower end of this tube projects into the space beneath the water-reservoir. Above the bottom of the water-reservoir a lateral hole g' is formed, communicating with the interior of the water-reservoir. Within the tube g is inserted a valve-stem g'', which is threaded therein and is pointed at its lower end, so as to close the lower end of the tube. The upper end of this stem g'' extends above the valve and is provided with a knob by which it may be readily turned.

Within the inner case or carbid-holder is placed a tube K, designed to form a connection between the spaces above and below the packing-ring B², so as to secure an equalization of pressure. This tube at its upper end is connected with a hole formed through the side of the inner case above the packing-ring B² and at its lower end with a hole which is preferably below the lower edge of the water-reservoir G. The lower end of the tube may, however, be connected with the outside of the inner case at any point below the packing-ring B², provided such connection is at a point that is not stopped by intimate contact with the inner wall of the water-reservoir.

A vent is supplied for the water-reservoir, so that gas may be admitted thereto when the water runs out. As herein shown, this vent consists of a tube G², extending from the bottom of the water-reservoir to near its upper end. This tube is open at top and bottom, forming a free connection between the space beneath the water-reservoir and the inside of the water-reservoir. Gas flows into the water-reservoir through this tube when the water flows out.

A blow-off valve, by which excessive pressure in the lamp is obviated, is provided. This blow-off valve is located in the bottom of the outer case and consists of a valve I', which is held against the lower side of the bottom by a spring I², said spring being retained in position by a cap I³. From this valve a tube I extends upwardly to a point where it is in constant communication with the interior of the lamp. As herein shown, this tube extends within the water-reservoir and terminates just short of the upper end of the reservoir.

The interior of the reservoir is in constant communication with the gas-chambers of the lamp through the tube G². The blow-off tube I is located close alongside the vent-tube G² and is in constant communication with the gas-chambers of the lamp. If by reason of any leakage of the valve F or by reason of

water which remains within the carbid-chamber when the valve is closed gas should be generated after the light has been turned off, this excess of gas will be discharged through the blow-off valve. This will prevent undue rise in pressure within the lamp and injury which might occur to the lamp therefrom. The burner J is connected to the cap A' and has a valve-stem J' extending to a point where it may be conveniently operated.

In Fig. 3 is shown a cartridge intended for use in connection with this lamp. As shown in Fig. 1, the carbid is placed immediately in contact with the inner case or carbid-holder C. In some cases it may be desirable instead of this construction to use a cartridge which when removed will remove the residue left from the decomposition of the carbid. This cartridge is constructed as shown in Fig. 3. It consists of two telescopic cups H and H', having their closed ends outward. These cups are made annular, having cylinders H² and H³ placed concentric with the outer walls and telescoping in the same manner as the cups H and H'. The cylinder H², which forms a portion of the lower cup, has a series of perforations h in its sides, through which the water is admitted to the carbid within the cup. These cups are provided with a longitudinal groove h' at one side, adapted to accommodate the pipe K, which is within the inner case C. These cups are made telescopic, partly because the lime resulting from the decomposition of the carbid is of greater bulk than the carbid. The cartridge being telescopic may extend as its contents increase in volume. Two or more of these cartridges may be supplied with each lamp, one cartridge being filled and ready to insert as soon as the old cartridge is removed.

In charging the lamp with carbid and water the valve g will be closed, so that the water cannot gain access to the carbid unless the use of the light is desired at once. When it is desired to light the lamp, the valve g is opened, admitting the water to the carbid. This feature is of manifest advantage, particularly where the lamp is used upon bicycles, carriages, or in locations where it is subject to constant or occasional shocks and changes of position. It furnishes an additional security against accidental admission of water to the carbid and the high pressures and waste of gas resulting therefrom.

Having thus fully described my invention, I claim as new and desire to secure by Letters Patent—

1. An acetylene-lamp, comprising an inner and an outer case adapted respectively to hold water and carbid, a diaphragm in the bottom of the outer case, a tube extending upward from the bottom of the inner case above the diaphragm and having holes establishing communication between the inner and outer cases, and a valve in said tube having a stem engaging the diaphragm, substantially as described.
2. An acetylene-lamp, comprising an outer

and an inner case adapted respectively to hold water and carbid, a diaphragm in the bottom of the outer case, a spring acting thereon to raise it, a tube attached to the bottom of the 5 inner case above the diaphragm, and having holes through its side and lower end connecting respectively with the inner and outer cases, and a valve sliding in said tube and adapted to close the holes in its side, and having a stem projecting downward into contact with the diaphragm, substantially as described.

3. An acetylene-lamp, comprising an outer and an inner case adapted respectively to hold 15 water and carbid, a diaphragm in the bottom of the outer case, a spring acting thereon to raise it, a tube attached to the bottom of the inner case above the diaphragm, and having holes through its side and lower end connecting 20 respectively with the inner and outer cases, and a valve sliding in said tube and adapted to close the holes in its side, and having a stem projecting downward into contact with the diaphragm, a cap for the upper end 25 of the tube, and a spring between the cap and the valve, acting to close the same, substantially as described.

4. An acetylene-lamp, comprising an outer and an inner case, adapted respectively to hold 30 water and carbid, a diaphragm in the bottom of the outer case, a valve in the bottom of the carbid-holder or inner case, having a stem engaging the diaphragm, a cap secured beneath the outer case, and a spring within said 35 cap and pressing upward against the diaphragm, substantially as described.

5. An acetylene-lamp, comprising an outer and an inner case adapted respectively to hold water and carbid, a diaphragm in the bottom 40 of the outer case, a spring acting thereon to raise it, a valve in the bottom of the carbid-holder or inner case, having a stem engaging the diaphragm, and a cap removably secured to the top of the outer case and inclosing the 45 inner case, said cap carrying the burner connection, substantially as described.

6. An acetylene-lamp, comprising an outer and an inner case adapted respectively to hold water and carbid, a diaphragm in the bottom 50 of the outer case, a spring acting thereon to raise it, a valve in the bottom of the carbid-holder or inner case, having a stem engaging the diaphragm, and a tube extending upward from the bottom of the outer case and between 55 its side and the side wall of the inner case, said tube opening at its upper end in the gas-space and at its lower end being provided with a blow-off valve, substantially as described.

7. An acetylene-gas lamp, comprising an 60 outer and an inner case adapted respectively to hold water and carbid, a spring-controlled diaphragm in the bottom of the outer case, a valve in the bottom of the case and controlled by the diaphragm, and a blow-off valve in the outer case, substantially as described.

8. A cartridge or removable carbid-holder for acetylene-lamps, comprising two telescopic

cups having their closed ends outward, the lower cup being provided with perforations for admission of water, the said cups being provided at one side with a longitudinal groove, substantially as described. 70

9. A cartridge or removable carbid-holder for acetylene-lamps comprising two telescopic cups having their closed ends outward, the 75 said cups being made annular and having cylinders placed concentric with the outer walls and telescoping in the same manner as the cups, the inner cylinder of the lower cup being provided with perforations, the said 80 cups having a longitudinal groove at one side, for the purpose set forth.

10. An acetylene-lamp, comprising an outer and an inner case, the inner case being adapted to receive the carbid, and having a pressure-controlled valve in its bottom for the admission of water, a compartment within the outer case, forming a reservoir within which the water may be retained and held from access to the carbid, and a valve in the bottom 90 of the reservoir, the stem of which extends outside the lamp, substantially as described.

11. An acetylene-lamp, comprising an outer and an inner case, the inner case being adapted to receive the carbid, and having a pressure-controlled valve in its bottom for the admission of water, an annular closed water-reservoir within the outer case and surrounding the upper part of the carbid-holder, and a valve in the bottom of the reservoir, having a 95 stem extending outside the lamp, substantially as described. 100

12. An acetylene-lamp, comprising an outer and an inner case, the inner case being adapted to receive the carbid, and having a pressure-controlled valve in its bottom for the admission of water, an annular closed water-reservoir within the outer case and above the carbid in the holder, a valve in the bottom of the reservoir, having a stem extending outside the lamp, and a vent connecting the upper part of the water-reservoir with the gas-space in the lamp, substantially as described. 110

13. An acetylene-gas lamp, comprising outer and inner cases, the latter serving as a carbid holder or generator, and having a pressure-controlled valve in its bottom for the admission of water, the upper part of the outer case being removable and the inner case having a supporting-flange held between the top and bottom parts of the outer case, an annular closed water-reservoir within the bottom part of the outer case and above the carbid in the inner case, a valve in the bottom of the water-reservoir, having an exterior operating-stem, a vent-pipe connecting the upper part of the water-reservoir with the space below it, and connections through the inner case between the top and bottom portions of the outer case, substantially as described. 115 120 125

14. An acetylene-gas lamp, comprising an outer and an inner case, the latter serving as a carbid holder or generator, and having a pressure-controlled valve in its bottom for the 130

- admission of water, the upper part of the outer case being removable and the inner case having a supporting-flange held between the top and bottom parts of the outer case, an 5 annular closed water-reservoir within the bottom part of the outer case and above the carbid in the inner case, a valve in the bottom of the water-reservoir, having an exterior operating-stem, a vent-pipe connecting 10 the upper part of the water-reservoir with the space below it, connections through the inner case between the top and bottom portions of the outer case, a spring-controlled blow-off valve in the outer case, and a tube extending 15 therefrom to the top of the water-reservoir, substantially as described.
15. An acetylene-lamp, comprising a case adapted to hold carbid and provided in its bottom with a pressure-controlled valve for 20 the admission of water, a case provided in its upper portion with a water-reservoir the lower portion of the case below the water-reservoir forming a space or chamber communicating with the interior of the carbid-case, and a valve controlled from outside the lamp for regulating the passage of water from 25 the reservoir to the said space or chamber communicating with the carbid-case, substantially as described.
20. 16. An acetylene-lamp, comprising a case adapted to hold carbid and having a pressure-controlled valve in its bottom for the admission of water, a case provided with a water-reservoir, and a chamber or space into which 30 the said water-reservoir opens, the said space or chamber being adapted for communication with the carbid-case through the pressure-controlled valve, a valve controlling the pas-

sage of water from the reservoir to said space or chamber, the said valve being controlled 40 from outside the lamp, and a blow-off valve connected with the gas-space of the lamp, substantially as described.

17. An acetylene-lamp, comprising an outer case adapted to hold water, an inner case having a pressure-controlled valve in its bottom, a tube located within the inner case and connecting the top and bottom portions of the outer case, and a removable cartridge or carbid-holder adapted to fit within the inner case and provided with a longitudinal groove 50 at one side adapted to receive the said tube, substantially as described.

18. An acetylene-lamp, comprising an outer and an inner case, the inner case being adapted 55 to receive the carbid and having a pressure-controlled valve in its bottom for the admission of water, the said outer case being provided in its upper portion with a compartment forming a reservoir for water, the lower 60 portion of the said outer case, forming a space or chamber communicating with the carbid-case, a tube extending through the reservoir and projecting at its lower end into the space or chamber in the lower part of the outer cas- 65 ing beneath the water-reservoir, the said tube being provided with a lateral opening communicating with the reservoir and a stem ar- ranged within the tube and adapted to close the opening in the lower end thereof, the up- 70 per end of the stem extending outside the lamp, substantially as described.
